UNITED STATES PATENT OFFICE.

HOWARD G. PETERS, OF DOUGLAS, WYOMING.

MACHINE FOR MAKING LOOPS.

SPECIFICATION forming part of Letters Patent No. 545,657, dated September 3, 1895.

Application filed April 17, 1895. Serial No. 546,066. (No model.)

To all whom it may concern:

Be it known that I HOWARD G. PETERS, a citizen of the United States, residing at Douglas, in the county of Converse and State of Wyoming, have invented a new and useful 5 Machine for Making Loops, of which the following is a specification.

This invention relates to an improvement in machines for making harness and other 10 loops.

The object of the present invention is to provide a simple and effective machine for clinching and securing the contiguous ends of 15 leather loops such as are used in the manufacture of harness.

A further object of the invention is to provide said machine with a novel form of spring-clamping arm for holding the ends of the loop while the die is operating upon the 20 clincher.

A further object is to provide means whereby said spring-clamping arm may be adjusted as to its position and tension.

To accomplish the objects above enumerated 25 the invention consists in certain novel features and details of construction and arrangement of parts hereinafter fully described, illustrated in the drawings, and pointed out in the claims.

In the accompanying drawings, Figure 1 is 30 a perspective view of the complete machine constructed in accordance with the present invention, being shown in the act of clinching a loop. Fig. 2 is a transverse vertical section through the machine, illustrating the operation of the machine and the function of 35 the several parts thereof. Fig. 3 is a detail perspective view of the grooved anvil. Fig. 4 is a similar view of the spring-clamping 40 arm. Fig. 5 is a similar view of the plunger, its die, and the knuckle-link by means of which the plunger is attached to the operating-lever. Fig. 6 is a similar view of one of the metallic clinchers. Fig. 7 is a sectional view in one of the completed loops, showing 45 the manner in which the clincher is applied thereto.

Similar numerals of reference indicate corresponding parts in the several figures of the 50 drawings.

Referring to the drawings, 1 designates a

C-shaped frame preferably cast in a single piece and formed in the process of manufacture with suitable base-flanges 2, which are perforated, as shown, adapting the device as 55 a whole to be secured to a table or other suitable support. At the forward end of the overhanging arm of the main frame the latter is provided with a vertical perforation 3, which serves as a bearing for a vertically- 60 movable plunger 4, said plunger being pivotally connected at its upper end to the operating-lever 5 by means of an interposed knuckle or link 6. The upper end of the plunger 4 is bifurcated, as shown, and embraces 65 a downwardly-projecting tongue 7 on the knuckle or link 6, being connected therewith by means of a pivotal pin 8. The upper end of the knuckle or link 6 is likewise slotted or bifurcated, adapting it to embrace 70 a lug 9, pendent from the lower face of the operating-lever 5, being pivoted thereto by means of a pin 10. The lower end of the plunger is provided with a cylindrical socket 75 into which is fitted the tapering shank of a die 12, said die being connected with the plunger by means of a dowel-pin 13, as shown, thus enabling the die to be removed, when desired, and replaced by another die of different size or shape. The operating-lever 5 80 may be of any desired size and length for affording the desired leverage, and is provided at its rear end with a perforated ear or extension 14, which is adapted to be received in a corresponding socket 16 in the overhanging 85 arm of the frame 1, being secured therein by means of a pivotal pin 17.

To the base of the main frame 1 is secured an anvil 18. Said anvil may be fixedly attached to the main frame in any preferred or 90 convenient manner and is provided with a forwardly-extending arm or rest 19, the upper face of which is provided with a pair of parallel grooves 20, said grooves merging into each other, as indicated, in such manner as to 95 form practically one groove with a central ridge, said ridge being located beneath the plane of the upper surface of said forwardly-extending arm 19. The anvil is further provided with a rearwardly-extending arm 21, 100 which has an upward extension 22 at the rear end, said extension being slotted or bifurcated,

as shown, for the purpose of receiving a downwardly-projecting ear or lug 23 on the rear end of a forwardly-extending spring-clamping arm. The extension 22 on the anvil and the 5 lug or ear 23 on the clamping-arm are provided with horizontally-aligned perforations for the reception of a connecting-pin 24, the perforation in the ear or lug 23 for the reception of said pin 24 being elongated vertically 10 for permitting the rear end of the clamping-arm to be adjusted in height for a purpose that will appear.

The spring-clamping arm designated at 25 is provided adjacent to its forward end with 15 a rectangular aperture 26, through which the die carried by the plunger is adapted to operate upon the clincher. In advance of said aperture in the clamping-arm the latter is provided with a pair of oppositely inclined or 20 flaring extensions or wings 27, which are preferably rounded on their under faces, as indicated, said wings or extensions projecting laterally upon either side of the grooved arm of the anvil and being adapted to be operated 25 upon by the thumbs of either hand for the purpose of elevating the clamping-arm to facilitate the insertion of the ends of the leather loop. The pressure with which the clamping-arm is caused to bear upon the loop may be 30 regulated by means of a set-screw 28, passing through said clamping-arm and engaging the anvil. In order to accommodate material of different thicknesses between the anvil and the clamping-arm the rear end of said clamping-arm may be elevated by means of the 35 vertical slot in its lug 23, before referred to. A U-shaped gage 29 is fastened to the clamping-arm and adjustable lengthwise thereof by means of a set-screw 30, the lower extremities 40 of the side arms of said gage projecting sufficiently beneath the lower face of the clamping-arm to serve as stops by means of which the position of the leather from which the loop is to be formed may be regulated, as desired. 45

In operation, the piece of leather from which the loop is to be formed is grasped at its ends between the thumb and forefinger of each hand, the ends being bent so as to meet 50 evenly at the top, thus forming a ring or loop with free ends. The loop thus formed is passed over the end of the grooved arm of the anvil, and as it is pushed inward the knuckles of the thumbs strike against the lower faces 55 of the flaring extensions 27, thereby lifting the clamping-arm and enabling the ends of the loop to be inserted between said clamping-arm and the grooved upper face of the anvil. Upon removing the thumbs the clamping-arm holds the contiguous ends of the 60 leather loop firmly together. The metallic clincher, the form of which is illustrated in Fig. 6, is now introduced into the rectangular aperture in the clamping-arm, points downward, when by depressing the operating-lever 65

5, the die at the lower end of the plunger forces the metallic clincher through the leather, the points, by reason of the particular shape of the double groove described, being turned or deflected inward beneath the leather and within the loop and securely and firmly clinched thereto, as indicated in Fig. 7. The loop now being complete, the same may be removed by sliding it forwardly off the grooved arm of the anvil. 70

It will be apparent that various changes in the form, proportion, and the minor details of construction may be resorted to without departing from the principle or sacrificing any of the advantages of this invention. 75

Having thus described the invention, what is claimed as new, and desired to be secured by Letters Patent, is—

1. In a machine for making loops, an anvil provided with a forwardly extending grooved 85 arm, a spring clamping arm located above said grooved arm, and the flaring extensions on said clamping arm for facilitating the elevation thereof, substantially as described.

2. In a machine for forming loops, an anvil 90 provided with a grooved face, in combination with a spring clamping arm located opposite to said grooved face and provided with an aperture for the reception and passage of the die, and also provided with oppositely flaring 95 wings or extensions for facilitating the lifting of the clamping arm, and means for adjusting the tension of said arm, substantially as described.

3. In a loop making machine, an anvil provided with a grooved arm, a spring clamping arm arranged adjacent thereto and provided with an aperture for the passage of the die, an adjustable gage for regulating the position of the material to be operated upon, 105 means for adjusting the tension of the clamping arm, and means for regulating the distance between the anvil and said clamping arm, substantially as described.

4. In a machine for making loops, an anvil 110 provided with an arm or rest having formed therein parallel grooves, a spring clamping arm arranged opposite to the grooved arm of the anvil and provided with an aperture for the passage of the die, an oppositely diverging 115 pair of wings or extensions on said clamping arm for facilitating the raising thereof while inserting the material to be operated upon, an adjustable gage for regulating the position of the material with relation to the die, and means for adjusting the distance between the clamping arm and the grooved arm or rest on the anvil, and means for regulating the tension of the clamping arm, substantially as and for the purpose specified. 120

5. In a machine for making loops, the combination with a supporting frame, of an anvil having a horizontal grooved arm, a spring clamping arm located above said anvil and provided with an aperture for the passage of 130

the machine die, the flaring wings or extensions at the forward end of said clamping arm for facilitating the lifting thereof, the adjustable gage for regulating the position of the 5 loop with relation to the die, and a set screw for adjusting and regulating the tension of said clamping arm, substantially as described.

In testimony that I claim the foregoing as my own I have hereto affixed my signature in the presence of two witnesses.

HOWARD G. PETERS.
